UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,296,095.

Specification of Letters Patent.

Patented Mar. 4, 1919.

Application filed July 25, 1917. Serial No. 182,651.

To all whom it may concern:

Be it known that I, LLOYD V. LEWIS, a citizen of the United States, residing at Edgewood borough, in the county of Allegheny and State of Pennsylvania, have invented certain new and useful Improvements in Railway Signaling, of which the following is a specification.

My invention relates to railway signaling, and particularly to signaling of the type comprising alternating current track circuits.

I will describe one form of signaling system embodying my invention, and will then point out the novel features thereof in claims.

In the accompanying drawings, Figure 1 is a view showing diagrammatically one form of signaling system embodying my invention, and Fig. 2 is a view similar to Fig. 1 but showing a modification thereof also embodying my invention.

Similar reference characters refer to similar parts in each of the views.

Referring first to Fig. 1, the reference characters 2, 2 designate the track rails of a railway over which traffic normally moves in the direction indicated by the arrow. The rails are divided, by means of insulated joints 3, into a plurality of successive track sections A—B, B—C, C—D, etc. Each track section is provided with a track circuit comprising the track rails themselves, means for supplying alternating signaling current of one frequency or another thereto, and two relays H and H'.

Each relay H and H', in the form here shown, is of the polyphase motor type, comprising two stator windings 4 and 5, and a rotor 6 which actuates the contact fingers. The winding 4, which I will term the track winding, is connected directly with the track rails of the corresponding section, while the other winding 5, which I will term the local winding, is supplied with alternating current independently of the track rails, the frequency of the current thus supplied to winding 5 being the same as one or the other of the frequencies supplied to the rails. I will assume herein that the two frequencies are 90 and 60 cycles respectively, although I do not wish to limit myself to currents of any specific frequencies.

For each track section I provide two

transformers U⁹⁰ and U⁶⁰, the primaries of which are connected to generators K and K' respectively, through the medium of transmission mains M. The generators K and K' deliver 90 and 60 cycle current respectively, hence the frequency delivered by each transformer is indicated by the exponent applied to the reference character U for such transformer. One terminal of the secondary of transformer U⁹⁰ for each section is connected with one terminal of the secondary of transformer U⁶⁰ for the same section, and a common wire O is connected with the junction of these two terminals.

The two relays for each section control the supply of current to the rails of the section in the rear, this control being such that when both relays are deenergized current of one frequency is supplied to the section in the rear, while current of the other frequency is supplied to said section when either one or the other of the relays is energized. As shown in Fig. 1, this control is effected through the medium of a slow-release relay W which is controlled by relays H and H' in such manner that relay W is deenergized when both relays H and H' are deenergized, and that relay W is energized when either relay H or H' is energized. The circuit for relay W when relay H is energized (see section A—B) is from the secondary of transformer U⁶⁰ through wires 60 and 7, contact 11 of relay H, wires 12 and 10, relay W, and common wire O to transformer U⁶⁰. When relay H' is energized, the circuit for relay W is similar (see section B—C) except that it includes wire 8 and contact 9 of relay H'. When relay W of any one section is deenergized, 60 cycle current is delivered to the rails of the section in the rear, the circuit being (see section C—D) from the secondary of transformer U⁶⁰ through wire 60, back point of contact 13 of relay W, wire 14, primary of a transformer P, and common wire O to transformer U⁶⁰. The secondary of transformer P is connected across the rails of the section in the rear. When relay W is energized, 90 cycle current is supplied to the rails of the section in the rear from secondary of transformer U⁹⁰ through wire 90, front point of contact 13 of relay W, thence as before.

The local winding 5 of each track relay H

- and H' is supplied with current of the frequency to which the relay is to respond, this supply being controlled by a back contact of the other relay H or H' of the same section.

5 This winding 5 of each relay H , which is the 90 cycle relay, is at times supplied with 90 cycle current through a circuit from the secondary of the adjacent transformer U^{90} , through wire 90, back point of contact 15 of relay H' , wire 16, winding 5, wires 17 and O to transformer U^{90} . Similarly, winding 5 of the 60 cycle relay H' is at times supplied with 60 cycle current through a circuit from the secondary of the adjacent transformer

10 relay H , wire 16, winding 5, wires 17 and O to transformer U^{90} . Similarly, winding 5 of the 60 cycle relay H' is at times supplied with 60 cycle current through a circuit from the secondary of the adjacent transformer

15 U^{60} through wires 60 and 7, back point of contact 18 of relay H , wires 19 and 20, winding 5, and common wire O to transformer U^{60} . It will be seen, therefore, that when either relay H or H' of a given track section

20 is energized, the local winding of the other relay is deenergized, so that there is no tendency for such other relay to chatter as would be the case if its two windings were supplied with currents of different frequencies.

25 For each track section I provide a signal S, which is adapted to indicate "stop", "caution", and "proceed". Each of these signals is controlled by the relays H and H' for the corresponding section in such manner that

30 the signal indicates "stop" when both relays are deenergized, "caution" when relay H' is energized and H is deenergized, and "proceed" when relay H is energized and H' is deenergized. As here shown, each signal

35 comprises three electric lamps R, Y and G, indicating when illuminated "stop", "caution" and "proceed", respectively. For reasons which will be pointed out hereinafter these lamps are in part controlled by contact

40 21 of relay W for the corresponding track section.

When both relays H and H' (see section C—D) are deenergized, relay W for such section is deenergized, and the circuit for the

45 "stop" lamp R of the signal for such section is then from secondary of transformer U^{90} , through wires 60 and 7, back point of contact 18 of relay H , wire 19, back point of contact 21 of relay W, lamp R and common

50 wire O to transformer U^{90} . This signal then indicates "stop". When relay H' is energized (see section B—C) relay W is also energized, and the caution lamp Y is illuminated, the circuit being from the secondary

55 of transformer U^{90} , through wires 60 and 7, back point of contact 18, wire 19, front point of contact 21 of relay W, lamp Y, and common wire O to transformer U^{90} . When relay

60 H is energized (see section A—B), the circuit for the "proceed" lamp G is from transformer U^{90} through wires 60 and 7, front point of contact 18 of relay H , wire 22, lamp G, common wire O to transformer U^{90} .

In the drawing I have shown a car or train

65 in track section C—D so that both relays H and H' for this section are deenergized and relay W is likewise deenergized. Signal S for this section consequently indicates "stop", 60 cycle current is then delivered to the rails of section B—C so that relay H' of the latter section is energized, because both of its windings are supplied with 60 cycle current. Signal S for track section B—C consequently indicates "caution". 90 cycle current is now delivered to the rails of section A—B so that relay H for this latter section is energized because both of its windings are supplied with 90 cycle current. Signal S for section A—B consequently indicates "proceed".

When train T passes out of section C—D, 80 into the next section in advance the rails of section C—D will be supplied with 60 cycle current so that relay H' will become energized and relay W will consequently pick up, thus causing the signal for this section to change from "stop" to "caution." The current supplied to the rails of section B—C will then be changed from 60 to 90 cycles, so that relay H' for this section will become deenergized and relay H will 90 become energized. During this change of frequency there will be an instant during which both relays H and H' are deenergized; that is, during which the front contacts of both of these relays will be open. 95 During this instant relay W will be deenergized, but owing to the fact that this is a slow-release relay its front contacts will not be opened. Consequently, during this instant contact 21 will not fall to its back point to illuminate lamp R, and there will therefore be no blinking of the lamps of signal S. For the same reason during the shift of frequencies in the rails of section B—C, contact 18 of relay W for this section 100 will not change its position, and consequently the rails of section A—B will continue to be supplied with 90 cycle current during the interval in which both relays H and H' of section B—C are deenergized. 105

The system shown in Fig. 1 provides for protection in case of broken down insulated rail joints. This is accomplished by connecting the secondaries of transformers P with the rails of the track sections in such manner that at any given instant the currents supplied to adjacent track sections, if of the same frequency, are 180° out of phase. Then if the insulated joints 3 between any two track sections should break down, the current reaching the relays of the forward section from the rails of the rear section would be in such direction that the relay, whose local element is energized at the same frequency, would be reversely energized, and, consequently, would be operated in such manner as to open its front contacts and close its back contacts. For instance, if the joints 3 at location A should break down 115 while the signal S for section A—B indi-

120 125 130 135

cates "proceed", 90 cycle current would be supplied to winding 4 of relay H from transformer P of the section in the rear of location A, and this 90 cycle current would be stronger than that received from transformer P of section A-B because the former transformer is much closer to the relay than is the latter. Relay H at location A would, consequently, be positively operated to the open position, and inasmuch as relay H' is already open, the signal S for section A-B would change to "stop" indication. Assume now that while section C-D is occupied by the train T the joints 3 at section C should break down. 60 cycle current would then be supplied to the windings 4 of relays H and H' at location C. This current would, of course, not coact with the 90 cycle current in winding 5 of relay H, and consequently this relay would continue to be deenergized. The 60 cycle current would, however, coact with 60 cycle current in winding of relay H' to positively hold this relay in the open position. The signal S for section C-D would, consequently, continue to indicate "stop". With this condition, if the train passes out of section C-D so that 60 cycle current is supplied to the rails of section C-D at the exit end thereof, relays H and H' would remain open because the voltage reaching relay H' from section B-C would overbalance that reaching this relay from the exit end of section C-D. Signal S for section C-D would consequently continue to indicate "stop".

Referring now to Fig. 2, the system here shown is similar to that shown in Fig. 1 except that the circuits are so arranged that both relays H and H' are energized when a proceed signal is to be given, and the slow release relays are omitted.

With the arrangement shown in Fig. 2, when both relays H and H' are deenergized (see section C-D), 60 cycle current is fed to the local winding 5 of relay H', and 90 cycle current is fed to the local winding 5 of relay H, as is the case in Fig. 1. The circuit for this winding 5 of relay H' is then from the secondary of transformer U⁹⁰ through wires 60 and 7, back point of contact 23 of relay H, wire 24, winding 5, wire O to transformer U⁹⁰. At the same time, the circuit for winding 5 of relay H is from secondary of transformer U⁹⁰ through wires 90 and 25, back point of contact 15 of relay H', wires 26 and 27, winding 5, and common wire O to transformer U⁹⁰.

If now, with relays H and H' deenergized, 60 cycle current is fed to the track rails (see section B-C), relay H' will become energized because both of its windings are supplied with 60 cycle current. Relay H will not be energized, but on the other hand the circuit for its winding 5 will be opened by the opening of back contact 15 of relay H',

hence relay H will not chatter. Thus far the system is in substance the same as that shown in Fig. 1.

Assume now that with H' energized and H deenergized (see section B-C), the current in the rails is shifted from 60 to 90 cycles. Relay H' will drop because of the different frequencies in its windings, whereupon contact 15 will supply 90 cycle current to winding 5 of relay H so that this relay will pick up. In so doing, however, this relay supplies its own winding 5 with 90 cycle current independently of contact 15 of relay H', the circuit being from secondary of transformer U⁹⁰ through wires 90 and 25, contact 28 of relay H, wires 29 and 27, winding 5, common wire O to transformer U⁹⁰. Hence the subsequent energization of relay H' by means about to be explained does not deenergize H. The closing of relay H closes a circuit supplying 90 cycle current to winding 5 of relay H', the circuit being from secondary of transformer U⁹⁰ through wires 90, 25 and 30, front point of contact 23 of relay H, wire 24, winding 5, common wire O to transformer U⁹⁰.

With 90 cycle current in the rails, then, both relays H and H' are energized, because windings 5 of both of these relays are also supplied with 90 cycle current (see section A-B).

The supply of current to the rails of each section is governed by relay H' of the section in advance. This current is 90 or 60 cycles according as the relay is energized or deenergized, and the control is effected by contact 31 in a manner which will be obvious from the drawing.

The lamps of signals S are controlled directly by the contacts of relays H and H'. The stop lamp R is illuminated when both relays H and H' are deenergized (see section C-D), the circuit for this lamp being from transformer U⁶⁰ through wires 60 and 7, back point of contact 32 of relay H, wire 33, back point of contact 34 of relay H', wire 35, lamp R and common wire O to transformer U⁶⁰. When relay H' is energized and relay H is deenergized the caution lamp Y is illuminated (see section B-C) the circuit being the same as the circuit for lamp R up to and including wire 33, then through front point of contact 34 of relay H', wire 36, lamp Y, and common wire O to transformer U⁶⁰. When both relays H and H' are energized, the proceed lamp G is illuminated (see section A-B), the circuit being from transformer U⁶⁰, through wires 60 and 7, front point of contact 32 of relay H, front point of contact 37 of relay H', wire 38, lamp G, and common wire O to transformer U⁶⁰.

The operation of the apparatus is as follows:

Section C-D being occupied by a car or

70

75

80

130

train T, both relays for this section are de-energized so that the signal S for this section indicates stop. Sixty cycle current is therefore supplied to the rails of section 5 B—C so that relay H' of the latter section is energized and relay H is deenergized. Consequently, signal S for section B—C indicates caution. Ninety cycle current is supplied to the rails of section A—B so that 10 both relays for the latter section are energized and the signal S for the latter section indicates proceed.

When the car or train T passes out of section C—D into the next section in advance, 15 relay H' for section C—D will become energized, thereby causing the caution lamp Y of this section to become illuminated. 90 cycle current will then be supplied to the rails of section B—C, whereupon relay H 20 for this section will become energized, thus supplying 90 cycle current to its winding 5 and also to the winding 5 of relay H' so that both relays for section B—C are energized. The proceed lamp G of this section B—C 25 then becomes illuminated.

Although I have herein shown and described only two forms of signaling systems embodying my invention, it is understood that various changes and modifications may 30 be made therein within the scope of the appended claims without departing from the spirit and scope of my invention.

Having thus described my invention, what I claim is:

35 1. A railway signaling system comprising a plurality of track sections, two relays for each section receiving energy from the rails of the section and responsive respectively to alternating currents of two different frequencies, means controlled by the relays of 40 each section for supplying current of one of said frequencies or the other to the rails of the section in the rear, and signals controlled by said relays.

45 2. A railway signaling system comprising a plurality of track sections, two relays for each section receiving energy from the rails of the section and responsive respectively to alternating currents of two different frequencies, means controlled by the relays of 50 each section for supplying current of one of said frequencies to the rails of the section in the rear when both relays are deenergized and for supplying current of the other frequency to the rails of the section in the rear when either relay is energized, and signals controlled by said relays.

55 3. A railway signaling system comprising a plurality of track sections, two relays for 60 each section each comprising a track winding and a local winding, each track winding receiving energy from the track rails of the corresponding section, means for supplying alternating current of one frequency or another to the rails of each section, means for

supplying the local windings of the relays for each section with currents of said two frequencies respectively, the supply of current to the local winding of each relay being controlled by a back contact of the other 70 relay for the same section, and signals controlled by said relays.

4. A railway signaling system comprising a plurality of track sections, two relays for each section each comprising a track winding and a local winding, each track winding receiving energy from the track rails of the corresponding section, means for supplying alternating current of one frequency or another to the rails of each section, means for 80 supplying the local windings of the relays for each section with currents of said two frequencies respectively, and signals for the sections controlled by said relays.

5. A railway signaling system comprising 85 a plurality of track sections, two relays for each section receiving energy from the rails of the section and responsive respectively to alternating currents of two different frequencies, means controlled by the relays of 90 each section for supplying current of one of said frequencies or the other to the rails of the section in the rear; and a signal for each section controlled by the relays for the section and indicating "stop" when both relays 95 are deenergized, "caution" when one relay is energized, and "proceed" when the other relay is energized.

6. A railway signaling system comprising a plurality of track sections, two track relays 100 for each section receiving energy from the rails of the section and responsive respectively to alternating currents of two different frequencies in the rails of the section, a slow release relay for each section controlled by 105 the track relays for the section and energized when either track relay is energized, means controlled by the slow release relay for each section for supplying current of one of said frequencies or the other to the rails of the 110 section in the rear, and signals controlled by said track relays and slow release relays.

7. A railway signaling system comprising a plurality of track sections, two relays for each section each comprising a track winding and a local winding, each track winding receiving energy from the rails of the corresponding section, means for supplying the local winding of one relay for each section with alternating current of one frequency, and the local winding of the other relay for each section with alternating current of another frequency, means controlled by a relay of each section for supplying alternating current of one of said frequencies or the 120 other to the rails of the section in the rear, and signals for the sections controlled by said relays.

8. A railway signaling system comprising a plurality of track sections, two relays for 130

each section each comprising a track winding and a local winding, each track winding receiving energy from the rails of the corresponding section, means for supplying the local winding of one relay for each section with alternating current of one frequency, and the local winding of the other relay for each section with alternating current of another frequency, means for supplying alter-

nating current of either of said frequencies to the rails of each section, and signals for the sections controlled by said relays.

In testimony whereof I affix my signature in presence of two witnesses.

LLOYD V. LEWIS.
